UNITED STATES PATENT OFFICE.

JOHN C. ROGERS, OF HOUSTON, TEXAS, ASSIGNOR OF ONE-HALF TO HOUSTON BLOW PIPE & SHEET METAL WORKS, OF HOUSTON, TEXAS, A CORPORATION.

APPARATUS FOR HANDLING LINT COTTON.

Application filed December 10, 1924. Serial No. 754,922.

This invention relates to new and useful improvements in an apparatus for handling lint cotton.

One object of the invention is to provide, in an apparatus of the character described, a conveyor flue for conveying the lint cotton from the linters to the condenser.

Another object is to provide a lint conveying flue provided with branches, which lead into the main flue from the linters, all so constructed and disposed that the lint cotton will follow a straight course through the main flue, and will not be subject to a rotary or whirling motion, and consequently will be delivered to the condenser in a loose and uniform mass rather than in masses of unequal density.

With the above and other objects in view this invention has particular relation to certain novel features of construction, operation and arrangement of parts, an example of which is given in this specification and illustrated in the accompanying drawings, wherein:—

25 Figure 1 shows a plan view of the complete apparatus embodying my improved arrangement and construction of flues.

Figure 2 is a cross sectional view taken on the line 2—2 of Figure 1.

30 Figure 3 shows a side elevation thereof, and

Figure 4 shows an enlarged fragmentary plan view.

Referring now more particularly to the drawings, wherein like numerals of reference designate similar parts in each of the figures, the numeral 1 designates the condenser, of any desired construction, the numeral 2 designates the suction fan and the numeral 3 designates the dust collector. A suction flue 4 leads from the condenser to the fan and continues on to the dust collector, forming the discharge flue 5.

There are the spaced series of linters 6, of well known construction, and arranged between these there is a lint flue 7 which delivers the lint to the condenser. The linters are preferably, arranged in pairs, one on each side of the flue 7 which is preferably rectangular in cross section. The flue 7 is formed with sections, each section being smaller than the adjacent section toward the condenser, so that the capacity of the flue is increased from its outer end, as it approaches the condenser.

Leading from the linters are the lint feed flues 8, 8 the feed flues of each pair of linters entering the outer end of the corresponding section of the flue 7, on opposite sides of said flue. These feed flues are, preferably, cylindrical but their delivery ends are flattened, as at 9, forming wide discharge openings, as 10, and said discharge ends 9 are turned forwardly, as shown in Figures 1 and 4, so that the lint will be delivered from them into the flue 7 in a longitudinal course rather than diagonally. This arrangement prevents the lint, from opposing feed flues, from being thrown together and formed into a dense mass, and permits the lint from all of the feed flues to move in a substantially uniform mass along the flue 7. Since the flue 7 gradually enlarges, section by section, the current of air passing therethrough will not be liable to set up a whirling movement and consequently the lint will not be thrown into masses of varying densities. This result is also accomplished more effectively by reason of the flat bottom of the lint flue. 80

The outer end of the flue 7 is left open, as at 11, to permit inspection of the interior of the flue and to permit unclogging should the flue become clogged.

What I claim is:—

1. A lint flue formed of sections gradually enlarging toward the discharge end of said flue and feed flues entering the inlet end of said respective sections, the entering ends of the feed flues being parallel with said lint flue. 90

2. A lint flue formed of sections, each section being larger than the preceding section, and feed flues having wide discharge ends entering the inlet ends of the flue sections parallel therewith. 95

3. A lint flue formed of sections and gradually enlarging toward its discharge end, and feed flues having wide discharge ends entering the inlet ends of said section, the entering ends of said feed flues being turned into parallel relation with the axis of said lint flue. 100

4. A lint flue formed of sections and gradually enlarging toward its discharge end, and feed flues entering the inlet ends of said section, the delivery ends of said feed flue being flattened and turned into parallel relation with the axis of the lint flue. 110

5. A lint flue whose capacity increases from its inlet to its discharge end and whose bottom is substantially flat, feed flues spaced apart and discharging into said lint flue and whose entering ends are substantially parallel therewith. 35
6. A lint flue whose capacity increases from its inlet to its discharge end, feed flues discharging into said lint flue and spaced 10 apart, the discharge ends of the feed flues being fastened and turned into parallel relation with the axis of the lint flue. 40
7. In combination a series of linters, spaced apart, a condenser, a lint flue dis- 15 charging into the condenser, said flue enlarging toward the condenser and feed flues from the respective linters and entering the lint flue, the entering ends of the feed flues being flattened and turned into parallel relation with the lint flue. 45
8. In combination a series of linters, spaced apart, a condenser, a lint flue dis- 20 charging into the condenser, said flue enlarging toward the condenser, and feed flues leading from the linters and into the lint flue, the discharge ends of the feed flues being flattened and turned into substantially parallel relation with the axis of the lint flue. 50
9. A lint flue formed of sections and gradually enlarging toward its discharge end and having a flat bottom, feed flues entering the inlet ends of said sections, and having their delivery ends flattened and 25 turned into parallel relation with the axis of the lint flue. 55
10. A lint flue whose capacity increases from its inlet to its discharge end and whose bottom is flat, feed flues discharging into the lint flue on lines parallel therewith. 40
11. A lint flue having a flat bottom and whose capacity increases from its inlet to its discharge end, feed flues which discharge into said lint flue, the discharge ends of the feed flues being flattened and turned into parallel relation with the axis of the lint flue. 45
12. A lint flue formed of sections, a section being larger than the preceding section, the bottom of said flue being substantially flat and horizontal, and feed flues having wide discharge ends entering the inlet of the larger flue sections. 50
13. A lint flue formed of sections, a section being larger than the preceding section, the bottom of said flue being substantially flat and horizontal, and feed flues having discharge ends entering the inlet end of the larger flue section. 55
14. A lint flue formed of sections, a section being larger than a preceding section, and feed flues having wide discharge ends entering the inlet end of the larger flue section and parallel therewith. 60

In testimony whereof I have signed my name to this specification. 65

JOHN C. ROGERS.
